UNITED STATES PATENT OFFICE

104,027

DESIGN FOR A TEXTILE FABRIC OR SIMILAR ARTICLE OF MANUFACTURE

John F. Gaul, Jr., Clifton, N. J., assignor to
Botany Worsted Mills, Passaic, N. J., a corpora-
tion of New Jersey

Application December 10, 1936, Serial No. 66,426

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The area contained within the dot and dash lines constitutes one design unit, which unit is repeated in the relation indicated over the entire face of the fabric.

The characteristic feature of the present design resides in the base fabric having a series of substantially continuous threads disposed vertically of the fabric and embodying series of cross-stitches spanning the vertically disposed continuous threads at intervals throughout their lengths.

I claim:

The ornamental design for a textile fabric or similar article of manufacture substantially as shown and described.

JOHN F. GAUL, JR.
